UNITED STATES PATENT OFFICE.

LEO F. ADT, OF ALBANY, NEW YORK.

NOSE-GUARD FOR EYEGLASSES.

No. 845,042.

Specification of Letters Patent.

Patented Feb. 26, 1907.

Application filed December 8, 1906. Serial No. 346,884.

To all whom it may concern:

Be it known that I, LEO F. ADT, of Albany, in the county of Albany and State of New York, have invented certain new and useful Improvements in Nose-Guards for Eye-glasses; and I do hereby declare the following to be a full, clear, and exact description of the same, reference being had to the accompanying drawings, forming a part of this specification, and to the reference-numerals marked thereon.

My present invention relates to improvements in nose-guards for eyeglasses; and the object of the invention is to provide an improved form of nose-guard having a relatively rigid supporting portion and a relatively movable or resilient nose-engaging portion arranged to yieldingly engage the fleshy portion of the nose to steady the eyeglasses and prevent slipping thereof, the yielding portions of the guard being sufficiently resilient to enable them to adjust themselves to the shape of the nose and to avoid undue pinching thereof.

To these and other ends the invention consists in certain combinations and improvements of the parts, all as will be hereinafter explained, the novel features being pointed out in the claims at the end of the specification.

In the drawings, Figure 1 is a perspective view of a portion of an eyeglass provided with a nose-guard embodying my present invention. Fig. 2 is a view of the mounting viewed edgewise of the lens. Figs. 3, 4, and 5 are perspective views of other forms of nose-guards embodying my invention.

Similar reference-numerals in the several figures indicate similar parts.

It is desirable in devices of this kind that they should be held in place before the wearer's eyes by nose-guards having relatively rigid portions which may be properly set by the optician in fitting the glasses and are adapted to rest on the solid or bony portion of the nose and supplemental nose-engaging portions adapted to be yieldingly pressed into the fleshy portion of the nose to prevent tilting or slipping of the eyeglasses, and this is accomplished according to the present invention by providing a pad or arm proceeding from a resilient bend formed therein at a point in rear of and substantially on the level with the lower nose-engaging portion of the guard to afford sufficient resiliency for the pad.

The guards shown in the present embodi-

ments are preferably composed of sheet material and adapted for attachment to the ordinary vertically-opening studs of eyeglasses, and in the form shown in Figs. 1 and 2 it embodies an attaching portion 1, connected to a downwardly-extending arm 2, preferably offset rearwardly of the plane of the lens, a lower nose-pad 3 proceeding forwardly and downwardly from this arm to provide a relatively rigid nose-engaging surface on the guard. The latter in this form is preferably offset inwardly from the plane of the arm 2 to bring this nose-engaging surface into the proper plane relatively to the nose-engaging surface of the supplemental pad, the latter in this form being attached to the guard proper by an arm forming a downward continuation edgewise of the supporting-arm, a bend 4 flatwise of the material being formed in this arm at a point in rear of and at about the same level of the lower nose-engaging portion to form a resilient or spring connection between the guard and the supplemental nose-engaging portion 5 that will permit the latter to swing with sufficient leverage from a point at or near the bottom of the guard, the top of this supplemental portion preferably extending upwardly above the point of attachment or center of the lens in order that it may engage the fleshy portion of the nose.

In the guard shown in Fig. 3 the lower nose-engaging portion 6 proceeds downwardly from the attaching-lug, and the supplemental nose-engaging portion 7 is resiliently or yieldingly connected to the bottom or lower portion of the guard by means of an arm 8, extending rearwardly from the rear edge of the lower nose-engaging portion and supporting a bend or convolution 9, the latter in the present instance proceeding from the upper edge of said arm and extending first outwardly, thence downwardly and inwardly beneath the arm to connect with the lower end of the supplemental nose-engaging portion, the supporting-arm being preferably offset outwardly to bring the nose-engaging surfaces of the guard in proper relation.

The guard shown in Fig. 4 is similar to that form just described, although the rearwardly-extending connecting-arm 10 is provided with a horizontal bend 11 to yieldingly support the supplemental nose-engaging portion and to bring its nose-engaging surface into proper relation with that of the lower nose-engaging portion. In the guard shown in

Fig. 5 the arm 12, connecting the supplemental nose-engaging portion and the guard proper extends rearwardly edgewise of the material of the guard at a point intermediate 5 its point of attachment and the lower nose-engaging portion, the arm proceeding downwardly to the lower portion of the guard, preferably in rear of the lower nose-engaging surface 1, thence doubling inwardly and upwardly to form a bend or loop 14, that will afford a comparatively long leverage for the supplemental nose-engaging portion and considerable length of metal to provide the desired resilient action without liability of breakage.

In each of the guards shown it is preferable that the supplemental nose-engaging surface being in the form of a pad or expanded portion at its upper end, so as to engage a sufficient area of the skin as to avoid undue pinching, and the narrowed arm may be adjusted so that it may or may not engage the nose as a nose-engaging surface, as may be desirable or advantageous in each case, the 25 offset connection between the nose-engaging surfaces causing them to stand in edgewise relation to each other, so that their flat surfaces may serve as nose-engaging surfaces.

Nose-guards constructed in accordance 30 with the present invention will be found to be efficient in use, and they can be produced cheaply, as all of the forms shown may be formed of a single piece of sheet material.

I claim as my invention—

35 1. A nose-guard for eyeglasses composed of flat material embodying lower and supplemental nose-engaging portions arranged in edgewise relation and connected by a resilient bend flatwise of the material and arranged on substantially the same level with the lower nose-engaging portion.

40 2. A nose-guard for eyeglasses embodying a lower nose-engaging portion, a supplemental nose-engaging portion arranged in rear of the lower portion, and an arm connecting the said nose-engaging portions having a resilient bend therein transverse of the plane of the nose-engaging surface of the guard and arranged at the lower portion of the guard.

45 3. A nose-guard for eyeglasses composed

of a single piece of flat material embodying an attaching portion, a lower nose-engaging portion, a supplemental nose-engaging portion arranged edgewise to the lower bearing portion and extending above the point of attachment thereof, and a connecting-arm proceeding edgewise from the guard and having a resilient bend therein flatwise of the material at a point in rear of and at substantially the same level with the lower nose-engaging 60 surface.

4. A nose-guard for eyeglasses composed of sheet material and embodying a lower holding-pad, a supplemental pad arranged above the holding-pad, and a reduced elongated nose-engaging arm arranged edgewise of the holding-pad and extending upwardly from the lower portion of the holding-pad.

5. A nose-guard for eyeglasses composed of sheet material and embodying an attaching portion, a lower nose-engaging portion, a supplemental nose-engaging portion or pad arranged above and in rear of the lower nose-engaging portion, and an elongated arm arranged edgewise of the lower nose-engaging 75 portion and connecting the latter and the supplemental pad, said arm having a resilient portion therein at the lower portion of the guard and formed by a flatwise bend of the material.

6. In eyeglasses, the combination with a lens of a nose-guard adapted to be attached thereto composed of sheet material and embodying an attaching portion, a supporting-arm extending downwardly therefrom and offset rearwardly of the plane of the lens, a lower nose-engaging portion extending forwardly and downwardly from said arm, a supplemental nose-engaging pad, and an elongated resilient arm therefor forming a 80 continuation of the offset supporting-arm and arranged edgewise of the lower nose-engaging portion, said arm having a bend therein flatwise of the material at a point adjacent to the lower nose-engaging portion.
